UNITED STATES PATENT OFFICE

144,285

DESIGN FOR A GAME BOARD

William J. Burnett, San Antonio, Tex.

Application May 15, 1945, Serial No. 119,558

Term of patent 14 years

(Cl. D34—5)

To all whom it may concern:

Be it known that I, William J. Burnett, a citizen of the United States of America, residing at San Antonio, county of Bexar, and State of Texas, have invented a new, original, and ornamental Design for a Game Board, of which the following is a specification, reference being had to the accompanying drawing, forming a part thereof wherein:

The figure is a top plan view of a game board showing my new design. The article is of conventional thickness.

I claim:

The ornamental design for a game board, as shown and described.

WILLIAM J. BURNETT.
